UNITED STATES PATENT OFFICE.

MONTGOMERY WADDELL, OF NEW YORK, N. Y., ASSIGNOR OF ONE-THIRD TO EDWARD B. ALDRICH, OF NEW YORK, N. Y., AND ONE-THIRD TO HAROLD T. G. VAN DER LINDE, OF PLAINFIELD, NEW JERSEY.
PAPER BARREL.

1,128,826.

Specification of Letters Patent. Patented Feb. 16, 1915.

Application filed June 6, 1911. Serial No. 631,561.

To all whom it may concern:

Be it known that I, MONTGOMERY WADDELL, a subject of the King of Great Britain, residing in the borough of Manhattan, 5 city, county, and State of New York, have invented certain new and useful Improvements in Paper Barrels; and I do hereby declare the following to be a full, clear, and exact description of the invention, such 10 as will enable others skilled in the art to which it appertains to make and use the same.

The invention contemplates an improved construction of a paper or pulp barrel or 15 keg with the object of adapting it to better advantage for use as a container for liquids.

It consists primarily in providing the usual cylindrical body portion with outwardly flared ends forming conical seats upon which heads with conical edge walls 20 may be tightly fitted and secured by metal head-hoops or bands which encircle the flared ends of the body portion and are bent or crimped down against the seated 25 heads.

The invention further consists in providing a perforated strengthening partition midway of the barrel, which partition, 30 in addition to strengthening the body of the barrel, acts as a baffle to prevent the whole contents of the barrel from being projected against one head and its holding hoop or band when the barrel is handled.

In the drawing, Figure 1 represents a 35 longitudinal section of a barrel embodying the several features of this invention; Fig. 2, represents a transverse section of the same taken through one of the compartments; and Fig. 3, represents a detail in section illustrating the manner in which the rings are applied.

The body of the barrel consists of a cylinder A which may be built up of layers 45 of paper or pulp upon a suitable mandrel. Before the cylinder A is dried or otherwise rendered hard and permanently shaped, rings B of the form shown in Fig. 3 of the drawing are placed upon it, and its ends 50 are then flared outwardly, forming conical seats for the heads C, which have corresponding conical peripheral walls. The rings B are conical to fit the outer surfaces of the flared ends and when applied as

shown at the bottom of the barrel in the 55 drawing, extend beyond the ends of the body cylinder. After the heads C have been seated in the conically flared cylinder, ends of the projecting parts of the rings B are 60 pressed, formed, or crimped over the ends and against the heads holding them securely in place as shown at the top of the barrel in the drawing. This construction admits of a tight fit even though there may be a variation in the size of the heads, or 65 of the cylinder, as the ring can be crimped tightly down against the head whether it has a shallow or a deep fit in its conical seat, the flange g providing sufficient material for this purpose. Furthermore, the 70 construction has the advantage that should the heads shrink or otherwise tend to loosen, they may readily be tightened by forcing them still farther down upon their conical seats, and correspondingly crimping the 75 rings down farther upon them. The heads are prevented from rising from their seats by the rings crimped against them which in turn are prevented from coming off the ends of the barrel by their engagements with the 80 outer conical surfaces of the flared ends of the cylinder.

It is desirable to prevent the projection of the entire contents of the barrel against one head, as would occur when, for instance, 85 the filled barrel is thrown upon end upon the ground from a truck, and I therefore prefer to protect the heads and their holding hoops by placing a perforated partition D midway within the barrel. This prevents 90 the contained liquid from moving too quickly from end to end of the barrel, and also strengthens the central portion of the cylinder A. I place this partition D in the cylinder A while the latter is still soft or 95 moist and roll in beads e from the soft wall of the cylinder to hold it in place. In order to further insure the stability of the partition, I likewise provide the barrel with a 100 protecting metal hoop F, having grooves f of a configuration conforming to that of the beads e.

Having thus described my invention, what I claim is:

1. A paper barrel, comprising a body portion having outwardly flared ends, heads having conical edge walls seated in said outwardly flared ends, the edges of said flared

ends extending beyond the heads, and metal hoops fitted to the outer conical surfaces of said outwardly flared ends and bent over inwardly into pressure contact with said heads; substantially as described.

2. A paper barrel, comprising a body portion having outwardly flared ends, heads having conical edge walls seated in said outwardly flared ends, the edges of said flared ends extending beyond the heads, and metal hoops fitted to the outer conical surfaces of said outwardly flared ends and bent over inwardly into pressure contact with said heads, said hoops being provided with an inner rim flange whereby should the heads tend to loosen, they may be readily tightened by correspondingly deepening the inward

bend of the hoops; substantially as described.

3. A paper barrel, having midway of its length a perforated diaphragm, engaged by annular beads projecting from the inner periphery of the body portion of the barrel, said barrel being further provided with a reinforcing hoop having annular projections from its inner periphery corresponding to said beads; substantially as described.

In testimony whereof I affix my signature, in presence of two witnesses.

MONTGOMERY WADDELL.
